(57) **CLAIM**

The ornamental design for a toaster fork, as shown and described.

DESCRIPTION

FIG. 1 is a perspective view of a toaster fork showing our new design;

FIG. 2 is a front view thereof;

FIG. 3 is a right side view thereof;

FIG. 4 is a back view thereof;

FIG. 5 is a left side view thereof;

FIG. 6 is an enlarged top view thereof; and,

FIG. 7 is an enlarged bottom view thereof.

The broken lines of FIGS. 1-7 form no part of the claimed design.

1 Claim, 2 Drawing Sheets
